BREATHING APPARATUS

Kurt A. Gerson, London, England

Application October 16, 1934, Serial No. 748,496
In Germany June 26, 1930

7 Claims. (Cl. 183—1)

This invention relates to breathing apparatus of the self-contained, or regenerative, type, for the use of miners, airmen, and others, in atmospheres which are vitiated with matter injurious to the lungs or for any other reason are unbreathable.

Breathing apparatus of the type contemplated characteristically comprise a fitting to be worn upon the head (which fitting may be a mouth-piece, face mask, or head mask and will herein-after be referred to simply as a head fitting) and a flexible breathing chamber into which exhaled air is passed from the head fitting via a charge of material (hereinafter referred to as regenerating material) active upon contact with respired air either to absorb the water (H_2O) and carbon dioxide (CO_2) contents thereof, or to absorb H_2O and CO_2 and at the same time to supply to the air a replenishing charge of oxygen, to restore the air to its original condition. The treated air is returned to the head fitting for further breathing, being thus continuously inhaled, exhaled, regenerated and again inhaled. Regenerating compositions of the type referred to are well known in the art and per se form no part of this invention, for which reasons they require no detailed description.

A drawback of breathing apparatus of this type as known prior to my invention was that to replace an exhausted charge of regenerating material by a fresh charge has necessitated the suspension of use of the apparatus, and consequently the withdrawal of the wearer from his place of operation in the unbreathable atmosphere to a position where the atmosphere is breathable. This has been due to the fact that to gain access to the charge of regenerating material for its exchange by a fresh charge has involved opening the apparatus with consequent free access of the surrounding atmosphere into the interior thereof, coupled with the further fact that the recharging operation occupies a period of time considerably longer than the maximum period during which it would be safe or possible for the wearer of the apparatus to dispense with the action of the regenerating material.

In consequence of this difficulty the practice has been to use a large charge of regenerating material, but this has caused the apparatus to be somewhat bulky, and therefore cumbersome and heavy.

The major objects of the present invention are to overcome the foregoing and attendant difficulties in a simple and efficient manner, by providing an apparatus in which the air-regenerating material can be renewed at will in the presence of unbreathable atmospheres, without danger, and quickly, surely and easily, and further to reduce bulk and weight as compared with prior practice.

According to the present invention, the breathing apparatus is characterized by the provision of a regenerating unit containing a cartridge of regenerating material which is replaceable by another charge without substantial exposure of the interior of the apparatus (that is to say the internal space occupied by the air for respiration) to the external atmosphere. By this means, as will be understood, the foregoing practical drawbacks of previously known forms of regenerative breathing apparatus, (i. e., the necessity of performing the operation of replacing an exhausted charge of regenerating material by a fresh charge in an atmosphere which is breathable on account of the previous necessity for opening of the apparatus) is at once avoided. Furthermore, to eliminate the necessity of suspending use of the breathing apparatus during the recharging operation, the invention provides that said operation is capable of performance sufficiently rapidly to enable the user of the breathing apparatus to change the charge of regenerating material not only without access of the external atmosphere, but also without doffing the head fitting.

Another feature of the invention resides in the possibility of using cartridges of regenerating material which are small relative to the usual dimensions of the canisters customarily used in these apparatus. Thus, with a breathing apparatus incorporating this feature, the external dimensions of the part of the apparatus which accommodates the regenerating material may be quite small, with corresponding elimination of the bulkiness and heaviness characteristic of regenerative breathing apparatus as constructed, prior to my invention, or, in the case of breathing apparatus in which the part which accommodates the regenerating material is located within the breathing chamber, with corresponding increase of available air space within this chamber.

As will be appreciated by those skilled in the art, the constructional details of the invention may vary widely; that is to say, the structural form and arrangement of the parts whereby, in accordance with the broadest aspect of the invention, the cartridge or other container of regenerating material is rapidly replaceable upon exhaustion by another without exposure of the interior of the apparatus to the external atmosphere surrounding it, may vary considerably, largely in accordance with design and convenience in any given case, relatively to the general form and arrangement of the other parts of the apparatus.

In one preferred form of the invention, however, the replaceable container of regenerating material is accommodated within a casing through which it is slidable with a gas-tight fit, being manually insertable into the casing at one side thereof and ejectable therethrough at the

opposite side by the insertion at the first side of a second container to replace the first, which second container pushes the first out of the mounting as it is itself pushed thereinto. Such a casing is provided with openings in its wall for passage of the air therethrough. Thus there is provided a regenerating unit adapted to receive exhaled air, for regeneration, which achieves the objects of the invention.

As will be understood, with this preferred constructional form of the invention, the general effect characteristic of the invention, of the operation of replacing a spent container, or cartridge, by a fresh one being effectual without exposure of the interior of the apparatus to the external atmosphere, and therefore without need for the user of the apparatus to withdraw to an atmosphere which is breathable, is realized in an exceedingly simple and effective manner, for all that the user has to do is simply to push out the spent container by inserting a fresh one in its place in the mounting, and if, as is preferred in most circumstances, the containers for use with the improved apparatus are in the form of small cartridges, a stock of such cartridges may be readily carried by the wearer of the breathing apparatus for use in the manner referred to as and when required.

It is to be understood, however, that the invention includes not simply the use of containers in the form of small cartridges, but if desired, larger containers, for example, containers simulating in size the usual canister hereinbefore referred to.

The gas-tight sliding mounting for the container, according to the aforesaid preferred construction, may take any convenient form. In the case of the container being in the form of a small cartridge, it may be a rigid tubular casing open at both ends. In the case, on the other hand, of the cartridge taking the form of a large container, as referred to, the mounting may conveniently comprise two opposed saddles adapted to embrace and hold the container between them and ported to register with air inlet and outlet openings provided in the walls of the container, to place them in communication one with the head fitting of the breathing apparatus and the other with the breathing chamber thereof. In such a construction, the two saddles are preferably resiliently drawn or pressed towards one another so as to embrace and retain the container between them resiliently. This arrangement, as will be appreciated, serves to ensure or enhance gas-tightness of fit as between the relatively sliding surfaces of the container and the two saddles.

In addition, suitable packing means may be provided, as between said relatively sliding surfaces, still further to enhance gas-tightness of fit of these surfaces with one another, especially in the immediate neighborhood of the ports in the saddles.

Having in the foregoing outlined the principal features of the invention, several constructions embodying it will now be described by way of example of how the invention may be carried into effect, these constructions being described with reference to the accompanying drawings, of which Fig. 1 is a vertical sectional view through one form of breathing apparatus constructed in accordance with the invention; Fig. 2, a section on the line II—II, Fig. 1, showing a cartridge of regenerating material in operative position in the casing; Fig. 3, a view similar to Fig. 2 showing a spent cartridge being ejected by the insertion

of a fresh one; Fig. 4, a vertical sectional view on a somewhat larger scale than Figs. 1 to 3, showing a larger form of container accommodated in a modified embodiment; Fig. 5, a front view of the apparatus shown in Fig. 4; Fig. 6, a similar view to Fig. 4 showing another modified construction; Fig. 7, a fragmentary section corresponding to the upper part of Fig. 4 and showing a detailed modification of construction; and Fig. 8, a view similar to Fig. 4 illustrating a 10 modification.

Referring first to Figs. 1 to 3, the apparatus comprises a head fitting in the form of a face-mask indicated rather schematically by the numeral 1, a tubular casing 2 having in the rear an opening 3 in communication with the mask through a connection 4, preferably of rigid character. The front side of tubular casing 2 is provided with an opening 5, positioned opposite rear opening 3, leading to a connecting member 6. Exhaled air passes from the mask into connection 4, thence through a non-return valve 7 mounted rearwardly of opening 3, and through that opening into a cartridge 8 containing regenerating composition and disposed in casing 2. The air passes through the cartridge and passes into connector 6, thence through a flexible tube 9 to the breathing bag 10. From the breathing bag the air is returned to the mask through a flexible tube 11, which leads to one end of a conduit member 12 the other end of which opens into connection 4. Conduit 12 is provided with a one-way valve 13 adapted to permit regenerated air to return to the mask, but to prevent exhaled air from passing directly to the breathing bag, thus compelling it to pass to and through cartridge 8.

Cartridge 8 is provided in its wall with inflow and outflow openings 14 and 15, respectively, positioned to register with openings 3 and 5, respectively, of casing 2. Actually the cartridge will be filled with air-regenerating composition, but in the various figures it has been omitted to avoid obscuring details. Most suitably a foraminous member 16 is disposed longitudinally of the cartridge to cause the air passing through it to be well distributed throughout the regenerating mass.

Tubular casing 2 is open at both ends so that, as already described herein, the cartridges 8 are not only insertable into the casing from the side thereof, but also so that they may be pushed completely through the casing from the side at which they were inserted to the opposite side. Hence, upon a cartridge becoming exhausted a fresh cartridge can be pushed in its place in the mounting with simultaneous ejection of the displaced cartridge, which emerges of course from the side of the mounting opposite to the side at which the replacing cartridge is inserted. Fig. 2 shows a cartridge 8 in operative position in the casing, while Fig. 3 shows an exhausted cartridge 8 being ejected by insertion of a fresh cartridge 8a, as just described.

The tubular casing is also arranged to have a gas-tight fit with the inserted cartridges and to maintain this fit during the sliding in of the replacing cartridge and the sliding out of the displaced cartridge, so that the operation of changing a cartridge is effectual with maintenance of gas-tight isolation of the interior of the apparatus from the external atmosphere surrounding it. The interior of the apparatus is, of course, closed off from the external atmosphere at one of the open ends of the tubular casing by the advancing 70

end of the replacing cartridge 8a as this is being slid into position in the casing, and at the other end by the trailing end of the ejected cartridge 8. Fig. 3 illustrates this effect.

5 Referring next to Figs. 4 to 8, the container, or cartridge, 20, of regenerating material in the construction shown in these figures is of approximately rectangular form in horizontal section and of the oval form shown in vertical section. It is accommodated and resiliently held between an opposed pair of approximately arcuate saddles 21 which are urged toward one another by springs 22 connected to a backing plate 23 forming part of the apparatus.

10 15 As in the case of the tubular casing 2 of the previously described construction, container 20 of the construction of Figs. 4 and 7 is slideable with a gas-tight fit into and out of operative position between the two saddles 21. The gas-tight fit, however, is ensured by the resilient pressure of the saddles toward one another upon the contacting surfaces S of the top and bottom of the container, this resilient pressure being due partly to the action of the springs 22, and partly to 20 tension produced in a Bowden or like wire 24 anchored at its ends to the top and bottom of the backing plate, or frame member, 23. This wire is threaded through eyes 25 on inlet and outlet conduits 26 and 27 leading, respectively, to and 25 from the interior of the container 20. The wire bears upon the outer shoulders of the saddles 21, as shown, and is tightened by manipulation of a lever 28 pivoted at 29 to a palm 30 adapted to abut the face of the container.

30 35 In order to ensure or enhance gas-tightness of fit between the spring-pressed saddles 21 and the top and bottom surfaces respectively of the container 20, the said saddles are preferably provided with a resilient lining 31 of gas-impervious material, for example, absorbent material impregnated with a lubricant adapted both to impart gas-imperviousness to the absorbent material and also to serve as a lubricating agent to facilitate the insertion and simultaneous ejection of the containers into and out from position between the saddles. Alternatively, a gas-sealing and lubricating agent for the relatively sliding surfaces of the container and the saddles may be incorporated in the container wall; or again, 40 suitable lubricating fittings may be provided in the mounting for the container, these fittings being arranged to be maintained charged with soap, grease or other lubricant.

45 50 The ends of container 20 are provided with openings 32 and 33 positioned to register with inlet and outlet conduits 26 and 27, respectively, to permit passage of the exhaled air through the regenerating composition contained in the cartridge. When handle 28 is manipulated to actuate the Bowden wire to apply tension, conduit members 26 and 27 are urged inwardly, and the pressure on them acts on lining 31 to seal the 55 openings in the canister against leakage.

55 60 As shown in Fig. 5, the saddles 21 are preferably formed at the insertion end with a bell mouth, or outwardly turned lip, 34, to facilitate entrance of the leading end of the replacing container, as when this must be done in darkness or under other conditions which might render the replacing operation difficult. In order to render more easy and more certain the correct positioning of the newly inserted container in the mounting (that is to say so that the inlet and outlet openings 32 and 33 in the wall of the container shall 65 properly register with the inlet and outlet con-

duits 26 and 27) the arrangement is preferably such that when the container is properly positioned in the mounting the leading end is flush with the adjacent end faces of the saddles. With such an arrangement, the user of the breathing apparatus has simply to push the replacing container sufficiently far into the space between the saddles to bring the leading end of the container flush with said end faces of the saddles, whereupon he may rest assured that the interior of 10 his newly inserted container is in proper communication with the head fitting of the apparatus on the one hand (through conduit 26) and the breathing bag thereof (through conduit 27) 15 on the other.

15 The containers are moreover preferably provided with guide ribs 35, Figs. 4 and 5, to assist in guiding the container properly into position between the saddles and thereafter to prevent the container from rotating therein. In the construction shown in Figs. 4 and 5, there are two 20 such guide ledges, one extending along the upper part of the outer side wall of the container and the other along the lower part of the inner side wall.

25 30 The modification of construction shown in Fig. 6 resides in this, that whereas in the arrangement shown in Figs. 4 and 7 both of the saddles 21 are resiliently mounted, in the construction shown in Fig. 6 only one of the saddles 21a is so 35 mounted, the other, 37, being rigidly mounted upon the carrier plate, or frame member, 23a. In addition, instead of pressing the two saddles toward one another by a tautened Bowden wire, the resiliently mounted saddle 21a is pressed 40 toward the rigidly mounted saddle 37, and locked in operative position, by a cam lever 38 pivotally mounted upon the end of a bracket 39 projecting from the face of the carrier plate 23a. It will be appreciated, however, that any other convenient 45 means or arrangement may be employed for resiliently pressing and locking the two saddles together upon the intervening container.

45 50 Referring again to the inlet and outlet conduits 26 and 27 which communicate respectively with the head fitting of the apparatus and the breathing bag thereof, it will be seen from Fig. 4 that these branches (which are of identical construction) are formed at the inner end with a flange 40 which is received behind a cooperating flange 41 formed upon a boss portion 42 of the saddle 21, and that the pressure exerted by the tautened Bowden wire 24 thus operates to press each conduit toward its adjacent bearing surface against the canister through the intermediary of that part of the resilient liner 31 in the immediate neighborhood of the flange 40. By this means, as will be appreciated, the gas-tightness of fit as between the canister and the saddles is more especially ensured in the immediate 55 neighborhood of the inlet and outlet conduits 26 and 27.

55 60 An alternative mode of sealing the conduits is shown in Fig. 7. As in the preceding embodiment, conduit 26a is provided with a flange 40a 65 which underlies a flange 41a extending inwardly from the top of boss 42a formed on saddle 21b. In this instance, resilient liner 31a is provided with an opening corresponding in size to that of boss 42a, and a resilient gasket 43 is positioned on 70 top and on the lower side of flange 40a. As in the preceding embodiment, conduit 26a is urged downwardly by Bowden wire 24a acting through lug 25a, but in this modified construction it does so against the action of a coil spring 44 acting 75

between flange 41a and the shoulder 45 provided on conduit 26a. It will be understood that although this embodiment has been shown and described as applied only to the inlet conduit, it is 5 equally applicable to the outlet conduit.

When the Bowden wire is tightened it urges the conduit downwardly, so that the lower gasket 43 is pressed against the container to form an effective gas-tight seal between the container and the 10 conduit. With this construction, there is the advantage over the construction of Fig. 4, that when the Bowden wire is slackened (by rotation of the cam lever 28) to permit or facilitate insertion of a fresh container 29 between the saddles, the 15 flange 40a of the conduit is positively urged by spring 44 into gas-tight fit with the boss flange 41a of the saddle, so that if there should happen to be leakage path for the external atmosphere past the flange 40a, this path will be effectively 20 blocked by the upper gasket 43. Thus leakage is prevented under all conditions.

Fig. 8 shows a form of inlet conduit 25a somewhat different from that shown in Figs. 4 to 7. In this embodiment the bottom face of the conduit is convex, so that the sealing pressure created by the Bowden device is increased about the periphery of the cartridge opening 32. Of course, 25 this modification is applicable to both the inlet and outlet conduits, although shown as applied 30 to but one.

If desired, in order to preserve in fully active condition the charge of regenerating material in the cartridge or other container, the openings in the wall of the container may be normally (that 35 is to say, until the container is required to be used) closed by thin, air-impervious sheet material, for example, oiled paper.

The cartridges, as also the larger form of container referred to, may of course be of any desired shape other than the shapes described in the foregoing embodiments of the invention and illustrated in the accompanying drawings.

According to the provisions of the patent statutes, I have explained the principle and mode of 45 construction of my invention and have illustrated and described what I now consider to represent its best embodiment. However, I desire to have it understood that, within the scope of the appended claims, the invention may be practiced 50 otherwise than as specifically illustrated and described.

I claim:

1. In a self-contained breathing apparatus, an air regenerating unit for treating air exhaled by 55 the wearer of the apparatus, the unit comprising a cartridge of air-regenerating material provided with an inlet opening for passing exhaled air into the cartridge, and with an outlet opening for egress of the treated air, and cartridge-holding 60 means for receiving said cartridge slidably and adapted to make a gas-tight fit with the cartridge, said cartridge being so constructed that it is replaceable when another cartridge is inserted in direct contact therewith and that such contact prevents access of external atmosphere into the apparatus during the replacing operation.

2. In a self-contained breathing apparatus, an air regenerating unit for treating air exhaled by the wearer of the apparatus, said unit comprising 70 a tubular casing for receiving a cartridge of air-regenerating material, and a cartridge of air-regenerating material slidably mounted within said

casing and making a gas-tight fit therewith, the cartridge being provided with ports for passing exhaled air into and removing treated air from the cartridge, and a spent cartridge being ejectable from one side of the casing by a fresh cartridge 5 slidably inserted from the opposite side of the casing while substantially preventing access of external atmosphere into the apparatus.

3. In a self-contained breathing apparatus, an air regenerating unit for treating air exhaled by 10 the wearer of the apparatus, said unit comprising a mounting open at its sides for slidably receiving a cartridge of air-regenerating material and provided with an inlet opening for passing exhaled air into the material and with an outlet 15 opening for egress of the treated air, and a cartridge of air-regenerating material slidably mounted within said mounting and making a gas-tight fit therewith, said cartridge being provided with inlet and outlet openings adapted to register 20 with those of said mounting, said cartridge and mounting having means cooperating to insure register of the cartridge and mounting openings when the cartridge is completely inserted in the mounting, said cartridge being so constructed that it is 25 ejectable from one side of the mounting when another cartridge is inserted in direct contact therewith in the other side of the mounting and that such contact prevents access of external atmosphere into the apparatus during the replacing 30 operation.

4. In a self-contained breathing apparatus, an air regenerating unit for treating air exhaled by the wearer of the apparatus, said unit comprising a cartridge member having inlet and outlet 35 openings and containing air regenerating material, a frame, a mounting member including a pair of opposed saddles constructed to fit against opposite ends of the cartridge and permit sliding insertion and expulsion of the cartridge laterally of 40 the saddles, said saddles being provided with openings registering with said cartridge openings, and spring members carried by said frame urging said saddles against the ends of the cartridge, said cartridge being constructed so that it is readily ejectable 45 when another cartridge is pushed into the saddles in contact with it and that such contact substantially prevents access of external atmosphere into the apparatus during the replacing operation. 50

5. In a self-contained breathing apparatus in accordance with claim 4, releasable tensioning means acting on a saddle to provide gas-tight fit between the saddle and the cartridge during use, release of said tensioning means permitting expulsion of the cartridge through sliding insertion of another cartridge while substantially preventing access of external atmosphere into the apparatus. 55

6. In a self-contained breathing apparatus according to claim 4, means associated with one of said members cooperating with the other member to insure registry of the cartridge and saddle openings directly upon complete insertion of a cartridge. 60

7. In a self-contained breathing apparatus according to claim 4, the cartridge being provided with a rib member positioned to engage an edge of one of said saddles to insure registry of the cartridge and saddle openings directly upon complete insertion of the cartridge. 70

KURT A. GERSON.
